FLUSH VALVE

Claus D. Myer, Grantwood, N. J., assignor to
 Myer Flushometer Co., Grantwood, N. J., a
 partnership

Application February 15, 1946, Serial No. 647,815

4 Claims. (Cl. 251—159)

1

This invention relates to new and useful improvements in flushing valves and has especial reference to improvements over the general type of valve shown in my U. S. Patent No. 1,722,155 issued to me July 23, 1929 and entitled "Flush Valves."

An object of the invention is to provide a valve in which are eliminated the sudden shocks, due to high water pressure, to the parts of the valve upon either opening or closing of the valve.

A further object is to provide a device which is simple, efficient, durable, economical to manufacture, capable of ready adjustment and repair and operable by the user with the utmost ease.

Further and more specific objects, features, and advantages will more clearly appear from the detailed specification hereinafter set forth especially when taken in connection with the accompanying drawings which illustrate a present preferred form which the invention may assume and which form part of the specification.

In the briefest and most general terms the invention comprises the following general features:

1. A valve stem, a valve moveable relative the stem, and means on the stem to limit the movement of the valve thereon in either direction;

2. A valve seated on its seat, a stem capable of moving up and down somewhat while the valve is on its seat, a cup-shaped cover on the stem above the valve to house the valve when the stem is down and means on the lower end of the stem to lift the valve off its seat when the stem has been raised a definite amount;

3. A cover to house the valve which when lifted will permit water to flow through the valve, which is perforated, even before the valve is lifted and which will permit water to flow through the valve even after the valve is seated until the cover is in fully housing position with respect to the valve.

The present preferred form which the invention may assume is shown in the drawings of which,

Fig. 1 is a vertical cross section of the valve;

Fig. 2 is a plan view with a portion broken away;

Fig. 3 is an elevation of the valve and,

Fig. 4 is an elevation of the shell with its lower edge cut through in scalloped fashion.

Confining this portion of the specification to the specific structure shown in the drawings, it will be seen that the improved valve comprises a valve casing 10 provided with an interiorly fitted sleeve 11 acting as a valve seat and com-

municating with an external nipple 12. Water under pressure enters the valve casing 10 through an inlet pipe 13 and when the valve 14 is operated passes out through the outlet pipe 15 connected to the nipple 12. Valve 14 coacting with the seat 11 is guided preferably by a dependent spider 16.

The stem 17 of the valve passes upwardly through a closed cylinder 18 and its upper end 19 rides in a bore 19 in the cap 20 which threadably closes the top of the cylinder 18. A cup 21 is seated on a shoulder of the stem 17 and between it and the cap 20 there is disposed a coiled expansion spring 22 which tends at all times to move the stem 17 downwardly. It will be noted that the lower end of the cylinder 18 is flanged as at 23 and bolted or otherwise secured as at 24 to a flange 25 on the valve casing 10. The lower cylinder head is formed by a metal ring plate 26 and a packing ring 27 held in place between shoulders on the casing 10 and the cylinder 18. The ring plate 26 divides the upper chamber from the lower chamber and prevents sand, mud or other foreign matter from passing upwardly to interfere with the working parts. This is most important when the valve is used for marine use.

In the cylinder 18 the stem 17 is provided with a piston flange 28 beneath which is disposed a rubber cup-shaped piston 29 held in place by a shoulder 30 swaged out of the stem 17. Beneath the piston 29 is a hollow cylindrical shell 31 with its upper open end bearing against the piston 29 and its lower wall 32 bearing against the lower end of the stem 17. The shell 31 is held in this position by the upper end of the spider 16 which is reduced in diameter as at 33 and is fastened against the bottom wall of the shell 31 by means of a screw stud 34 extending from the bottom of the spider 16 through a small hole in the lower wall 32 of the shell 31, and thereby also holds the shell 31 in place. The shell 31 as seen moves up and down with the stem 17 and fits somewhat loosely in the ring plates 26 and 27 so that high pressure water may leak therefrom around the pipe 13 and get into the cylinder 18.

This high pressure water will fill the cylinder both above and below the piston 29 and can pass from one side to the other of the piston 29 by way of connected by-pass passages, 36, 37, and 38 in which is disposed a check screw valve 39. To let out this water when desired removable screw plugs 40 and 41 are provided.

The stem 17 beneath the cup washer 21 is

provided with a slot 42 in which is disposed a circular plate 43 on an arm 44 connected to a collar 45 fastened to a squared portion 46 of a shaft 47 to one end of which an operating handle 48 is connected. The inner end of this shaft is reduced in diameter as at 49 and is seated in a suitable bore in the cylinder wall. A screw nut 50 around the outer end of shaft 47 acts as a packing. It will be noticed that the handle 48 connected to the end of shaft 47 is bent around at 51 parallel to the shaft 47 and that its operating end is then bent downwardly and at right angles to the shaft 47 as shown at 52. This downward angle is rather sharp as seen in Fig. 1 for a reason later to be set forth.

Returning now to the valve 14 it will be seen that it is of annular shape and not a solid valve and that it has a central large opening 53 therein which is very slightly larger than the diameter of the reduced portion 33 of the spider 16 above mentioned so that the valve 14 may move relatively to that portion of the spider and vice versa. The lower end of each leg of the spider 16 is curved outwardly as at 54 to slide snugly within the sleeve valve seat 11. The lower end of the shell 31 extends below the wall 32 and its lower edge or circumference is cut through to form a series of scallops 55 as shown in Fig. 4. The valve 14 also on its outer periphery 56 is tapered upwardly to fit into the similarly shaped inner wall of the lower end of the shell 31.

Now considering the operation of the structure thus above described, it will be clear that when the user is seated on the flush closet the valve may be back of him and the slope downwardly of the handle permits it to be operated by his merely moving back and pressing against the end of the handle with his back. When the handle is operated it turns the shaft 47 raising the arm 44 and consequently the stem 17 against the resistance of the expansion spring 22.

High pressure water from inlet pipe 13 has already leaked past the plate 26 and packing ring 27 and filled the cylinder 18. The movement of the piston 29 upwardly with the stem will be possible because the liquid in the cylinder 18 will be by-passed from the top of the piston 29 to the bottom thereof through the passages 36, 37 and 38 above mentioned and the rate of flow is determined by the setting of the check screw 39.

As the stem starts to rise it lifts the shell 31 but the valve 14 is not immediately lifted. However, as soon as the shell is lifted a small amount, the scalloped lower edge of it and the taper between its inner face and the valve 14 will immediately permit water at high pressure to flow around beneath the lower edge of the shell and up and around the valve and down through its central aperture 53 and between the legs of the spider to the outlet pipe 15. In other words the valve 14 stays on its seat at the beginning of the movement of the stem 17 and is not lifted off of it until the outwardly extending lower ends 54 of the spider legs engage the lower surface of the annular valve 14 to positively lift it off its seat.

Therefore at the very beginning of the stem movement upward the water is passed at a small predetermined rate and then when the valve 14 is raised from its seat the full flow is permitted. This prevents too sudden shocks to the valve and stem parts due to the sudden application of the high pressure water to the lower face of the valve. When the handle is released, in ac-

cordance with the operation of the spring described in the above mentioned patent, the stem slowly descends at a predetermined rate of speed and as it moves down it carries the cup or shell and the cup on its lower portion will descend also with the valve 14 resting on the flared legs 54 of the spider 16. As the downward movement continues the valve 14 will come to rest on its seat before the cup has entirely surrounded it and therefore during this time also a small amount of water will be allowed to flow until the cup entirely surrounds the valve and shuts off the water entirely.

Thus we have a valve relatively movable on a stem and limited in its movement thereon; with spider legs to lift the valve at the bottom of the stem; and a cover above the valve on the stem to house it when the stem is down; with means to permit small amounts of water to flow through the valve which is perforated before it leaves its seat and after it regains its seat until the respective lifting of the valve and the covering of the valve has been completed respectively.

While the invention has been described in detail and with respect to a present preferred form which the invention may assume, it is not to be limited to such details and forms since many changes and modifications may be made in the invention without departing from the spirit and scope of the invention in its broadest aspects. Hence it is desired to cover any and all forms and modifications of the invention which may come within the language or scope of any one or more of the appended claims.

What I claim as my invention is:

1. In a device of the class described a valve stem, an annular shaped valve having a tapered periphery and moveable along the stem within predetermined limits, means on the lower end of the stem to lift the valve from its seat when the stem is moved a predetermined distance upwardly, a cup-shaped element on the stem above the valve and having its lower edge cut through in scalloped fashion, said cup-shaped element having an inner tapered wall adapted to house and cover the valve on its seat when the stem is in its lowest position, the movement of the stem upwardly from its lower-most position lifting the cover to permit regulated small amounts of liquid to pass through the scallops and around and through the valve as soon as the cover is lifted and before the valve is lifted from its seat.

2. In a device of the class described a valve stem, an annular shaped valve moveable along the stem within predetermined limits, means on the lower end of the stem to lift the valve from its seat when the stem is moved a predetermined distance upwardly, a cup-shaped element on the stem above the valve and having its lower edge cut through to form one or more scallops, said cup-shaped element adapted to house and cover the valve on its seat when the stem is in its lowest position, the cover and the valve having cooperating adjacent tapered surfaces, the movement of the stem upwardly from its lower-most position lifting the cover to permit regulated small amounts of liquid to pass through the valve as soon as the cover is lifted and before the valve is lifted from its seat.

3. In a device of the class described, a valve stem, an annular valve with a tapered periphery relatively movable along the stem, a spider fixed to the lower end of the stem, the lower ends of the legs of the spider being outwardly flared and adapted to engage and lift the valve when

the stem is moved upwardly, a housing fixed to the stem and having a cup-shaped bottom with an inner tapered wall to receive and house the valve therein, the lower edge of said housing being cut through to form scallops, water passing through the scallops around the valve and through its central aperture when the housing is initially lifted.

4. In a device of the class described, a valve stem, an annular valve with a tapered periphery relatively movable along the stem within predetermined limits, means on the lower end of the stem to lift the valve from its seat when the stem has moved a predetermined distance upwardly, a housing fixed to the stem and having a cup-shaped bottom with an inner wall to receive and house the valve therein, the lower edge of the housing being cut through to form scallops to permit water to pass through the

scallops and around the valve and down through its central opening when the housing is lifted from the valve and before the valve has been lifted from its seat.
